INVENTOR.

Henry Wensink
BY
Cyrus W. Rice.

ATTORNEY.

UNITED STATES PATENT OFFICE.

HENRY WENSINK, OF GRAND RAPIDS, MICHIGAN.

FOUNTAIN PEN.

Application filed March 23, 1925. Serial No. 17,528.

To all whom it may concern:

Be it known that I, HENRY WENSINK, a citizen of the United States, residing at Grand Rapids, in the county of Kent and 5 State of Michigan, have invented new and useful Improvements in Fountain Pens, of which the following is a specification.

The present invention relates to fountain pens; and its object is, generally, to provide 10 such a pen improved in certain respects hereinafter appearing; and more particularly, to provide a fountain pen having improved means for venting the air therein in the operation of filling the pen with ink; and 15 further, to provide improved means for thus filling the pen.

These and any other objects hereinafter appearing are attained by, and the invention finds preferable embodiment in, the fountain 20 pen hereinafter particularly described in the body of this specification and illustrated by the accompanying drawings, in which:—

Figure 1 is a central longitudinal sectional view of a fountain pen;

25 Figure 2 is a like view thereof, seen from a slightly different angle, and showing the parts in another position;

Figure 3 is a side view of a piston and connected parts;

30 Figure 4 is a plan view of a valve;

Figure 5 is a side view thereof;

Figure 6 is a view of the plug whereby the pen "point" is held in the bottom of the pen; and

35 Figure 7 is a cross sectional view of the same taken on line 7—7 of Figure 6.

The fountain pen illustrated by the accompanying drawings has a hollow cylindrical barrel 1 adapted to contain the ink, 40 this barrel having a bottom comprising a plug 2 held frictionally and wedgingly or in any sufficiently tight and secure manner in the lower end of the hollow barrel, said bottom comprising also the plug 3 tightly fitting in the bore 4 of the plug 2, the pen "point" 5 being wedgingly held in said bore by the plug 3. This second plug 3 has the ink-feeding passage 6 leading from the interior of the barrel to the pen point, and 45 50 55 60 65 70 75 80 85 90 95 100 105 110

has also an air passage 7. A tube 8 carried by the plug 3 and extending upwardly therefrom in the barrel forms a continuation of this air passage. A sleeve 9 fits around the tube 8 and is slidable therealong by the knob 55 or handle 20 extending from the upper end

of the barrel. This sleeve has a port 10 in its side through which air may pass into the tube's upper end 21 when the sleeve is slid upwardly to the position seen in Figure 1, the port however being closed when the sleeve is slid downwardly to a position in which the port has passed below the upper end of the tube as seen in Figure 2. A piston 11 is slidable along the barrel and may be provided with piston rings 12. This piston has a central opening through which the sleeve passes, and at its lower side has a valve seat 13. The sleeve carries a conical valve 14 adapted to be moved into and out of seating position on the valve seat by the upward and downward movements respectively of the sleeve. A collar 15 is carried by the sleeve a short distance above the piston, which thus has a limited axial movement relatively to the sleeve between the valve 14 below and the collar 15 above the piston.

The barrel may be filled with ink by drawing the sleeve by its knob 20 upwardly, which operation sucks ink into the barrel through the same passage 6 through which the pen point is fed during its writing operation. The sleeve being then pushed downwardly the ink below the piston passes through the valve, which has been opened by the sleeve's downward movement, and through openings 24 in the collar 15. The sleeve being now drawn upwardly again causes more ink to be drawn through the passage 6. By repeating these operations, the barrel may be filled to the desired degree.

It will be seen that when the sleeve is drawn upwardly the air in the barrel above the piston is forced out through the open port 10, the tube 8 and the air passage 7; and that, the filling of the barrel being completed, the sleeve is pushed in to the position seen in Figure 2 wherein the port 10 is closed so that ink cannot pass therethrough.

It will be seen also that by the mechanism herein described and shown by the drawings a fountain pen is provided which is adapted to contain a great amount of ink, inasmuch as its barrel may be completely filled or almost so.

Caps 18 and 19 are shown in Figure 2.

In the illustrated form, the sleeve 9 has a hard rubber casing 22 around its upper portion, and is provided with a stop 23.

The invention being intended to be pointed out in the claims, is not to be limited to

or by details of construction of the particular embodiment thereof illustrated by the drawings or hereinbefore described.

I claim:

- 5 1. In a fountain pen: a hollow barrel adapted to contain ink and having a bottom carrying the pen point and having an ink-feeding passage to the pen point and an air passage; a tube extending upwardly in the barrel and forming a continuation of the air passage; a sleeve fitting around and slid-
10 able along the tube and having a port thereinto; a piston slidably fitting in the barrel and having a valve seat and a limited axial movement relatively to the sleeve; a valve carried by the sleeve and movable into and out of seating position on the valve seat by the sleeve's upward and downward move-
15 ments respectively.
- 20 2. In a fountain pen: a hollow barrel

adapted to contain ink and having a bottom carrying the pen point and having an ink-feeding passage to the pen point and an air passage; a tube extending upwardly in the barrel and forming a continuation of the air 25 passage; a sleeve fitting around and slid-
30 able along the tube and having a port thereinto open in an upwardly-slid position of the sleeve and closed in its downwardly-slid position; a piston slidably fitting in the barrel and having a valve seat and a limited axial movement relatively to the sleeve; a valve carried by the sleeve and movable into and out of seating position on the valve seat by the sleeve's upward and downward move-
35 ments respectively.

In testimony whereof I have hereunto set my hand at Grand Rapids, Michigan, this 20th day of March, 1925.

HENRY WENSINK.
